UNITED STATES PATENT OFFICE.

DORR H. HADSELL, OF BROCKTON, MASSACHUSETTS, ASSIGNOR OF ONE-HALF TO THOMAS D. BARRY, OF BROCKTON, MASSACHUSETTS.

PRESSER-FOOT ATTACHMENT FOR SEWING-MACHINES.

No. 853,874.

Specification of Letters Patent.

Patented May 14, 1907.

Application filed October 24, 1906. Serial No. 340,340.

To all whom it may concern:

Be it known that I, DORR H. HADSELL, a citizen of the United States, residing at Brockton, in the county of Plymouth and State of Massachusetts, have invented an Improvement in Presser-Foot Attachments for Sewing-Machines, of which the following description, in connection with the accompanying drawings, is a specification, like letters on the drawings representing like parts.

In the modern shoe factory, sewing machines are usually run at such speed that the leather is frequently injured, especially patent leather, the needle and presser foot frequently heating and softening the enamel of the leather so that the surface of the leather is roughened, the stock burned and the stitches rendered irregular. Accordingly I have devised the hereinafter described means for automatically applying a very thin film of oil to the leather at the points where it is being overlapped and stitched, whereby injury to the stock is prevented, the stitching is rendered uniform, the work is expedited, breakage of needles is prevented, lubricant is economized, and various other advantageous results secured.

In carrying out my invention I provide means for feeding oil in limited quantities to the presser foot and distributing the same in exceedingly small amounts in line with the surface or surfaces of the leather at the point where the pressure is applied thereto, and especially the stitching line where the greatest friction takes place by reason of the rapid in-and-out movement of the needle or needles.

The constructional details of my invention and further advantages and the operation thereof will be pointed out more at length in the course of the following description, reference being had to the accompanying drawings, in which I have illustrated one of the preferred embodiments of my invention.

In the drawings, Figure 1 is a top plan view of a presser foot provided with my invention; Fig. 2 is a bottom plan view thereof; Fig. 3 shows the same in side elevation, parts being broken away, viewing the left-hand side of Fig. 4; Fig. 4 is a front end view thereof; Fig. 5 is a side elevation looking at the right-hand side of Fig. 4; Fig. 6 shows my invention applied to the head of a sewing machine, viewed endwise; and Fig. 7 is a side

elevation thereof showing the forward end of 55 the sewing machine arm.

It will be understood that my invention is applicable to any usual or preferred type of sewing machine, and for convenience of illustration I have herein shown the overhanging 60 arm 1 of a typical sewing machine and have omitted most of the constructional details of the machine itself, as my invention can readily be understood without explaining the details of the usual sewing machine. At a 65 convenient point I provide a reservoir or fountain 2 of oil connected by a siphon pipe 3, to a stationary portion of the machine, being herein shown secured at 4 to the sewing machine arm 1 and thence extended downwardly adjacent the presser foot rod 5, where it is shown as terminating at 6, the usual needle carrier 7 and needles 8 being herein shown in position in front of the presser foot rod or carrier 5. The presser foot is herein 75 shown as comprising a usual wide, thin plate 9 and a block-like set piece 10 adjustably secured thereto by a slot 11 and set-screw 12 just behind the needle holes 13, said plate 9 terminating at its rear end in an upward extension 14 forming a split collar adapted to be clamped by a screw 15 to the rod or carrier 5. In the block 10 I provide a vertical channel or hole 16 and a lateral channel or hole 17, opening therefrom approximately in 80 line with the top surface of the adjacent portion of the work, i. e., approximately in line with or just above the bottom 18 of the plate 9. Secured to the top of the presser foot at 19 is a tube 20 which extends rearwardly and 90 then around the rear side of the presser foot at 21 to the inner side thereof, where it is bent upwardly at 22 to form a stem adapted to be secured by any suitable union 23 to the depending end of the siphon tube 3. At any 95 convenient place in the tube 20, preferably in the upwardly extending stem portion thereof, I provide a regulating valve 24. It will be understood that while I have thus described my invention in all its preferred 100 details, I do not intend to limit myself to this particular construction, as the supply tube may be connected with the oil-delivering ducts in a wide variety of ways, according to the particular construction of the machine 105 to which my invention is applied, the gist of my invention residing in providing, in connection with a sewing machine, means for de-

livering a thin film of oil to the leather surface at the points where the destructive or injurious friction takes place.

In use the operator places the two pieces of leather together, as for instance the vamp and toe cap of a patent leather shoe, the toe cap overlapping the front end of the toe portion of the vamp in usual manner, and then places them in the presser foot in position to be stitched together, the top piece being against the depending edge of the block portion 10 of the presser foot and engaged by the under side of the plate 9 while the adjacent portion of the vamp is engaged beneath the bottom part 10. In this position the duct 17 delivers a thin small line of oil to the adjacent surface of the top piece of leather and said oil is spread in an imperceptible film over the surface of the leather by contact with the bottom of the presser foot 9 while the duct 16 delivers a similar small portion of oil to the surface of the vamp, which is spread into a small almost imperceptible film by the bottom surface of the block or guide portion 10 of the presser foot, as the work is fed along beneath said presser foot. As the needles 8 reciprocate rapidly through the leather they are maintained properly lubricated by the oil delivered from the duct 17, so that they stitch freely and without unduly heating the leather. The result is that the stitches are uniform, whereas before it has been a common occurrence for the leather to stick or feed improperly, so that a number of stitches would be formed in approximately the same place in the leather, the rapid reciprocations of the needle resulting in cutting or severing the leather as well as burning it and melting the patent surface. My invention also permits the work to proceed not only with great uniformity but with extreme rapidity, and prevents the breakage of the needles, enables the operator to move and adjust the work with facility and to follow the pattern accurately. By having the pipe extend upwardly and then downwardly in the manner of a siphon I secure the delivery of the oil in the extremely attenuated manner and amount which I have found gives the best results, and

the delivery of oil may be further regulated, if found necessary in any given instance, by the valve 24. The movement of the presser foot is taken up by the spring action of the pipe 3 below its fastening 4, although any other convenient means permitting the desired movement may be provided, as by making the union 23 a telescoping union or by providing a section of rubber tubing or the like. I prefer to provide the short section of pipe 20 as an integral portion of each presser foot, as it permits the quick adjustment or change from one presser foot to another, as for instance for two, three or four-needle machines, etc. Also, while I prefer to distribute the oil from the presser foot itself, it will be understood that my invention is not limited in all cases to this construction, as it is sufficient in some instances to deliver the desired small amount or film of oil to the leather at the region of stitching, whether it is delivered directly from the presser foot, or not.

Having described my invention, what I claim as new and desire to secure by Letters Patent is,

1. In a sewing machine, a presser-foot for engaging flat upon the top surface of the work, and lubricating means including ducts opening on the flat work-engaging surface for maintaining the work-engaging surface of said presser-foot and the surface engaged thereby constantly lubricated.

2. In a sewing machine, a presser-foot having its work engaging surface formed in two different approximately parallel planes, and means for delivering independent portions of oil to said different work-engaging surfaces.

3. In a sewing machine, a presser foot, and means for delivering oil to lubricate the work-engaged thereby, said means including a fountain and a siphon pipe therefrom.

In testimony whereof, I have signed my name to this specification, in the presence of two subscribing witnesses.

DORR H. HADSELL.
